UNITED STATES PATENT OFFICE.

JOSEPH MARTIN PERRY, OF MERIDIAN, MISSISSIPPI.

DESIGN FOR A DISPLAY-RACK.

44,666.

Specification for Design.

Patented Sept. 16, 1913.

Application filed June 9, 1913. Serial No. 772,700. Term of patent 14 years.

To all whom it may concern:

Be it known that I, JOSEPH M. PERRY, a citizen of the United States, residing at Meridian, in the county of Lauderdale and State of Mississippi, have invented a new, original, and ornamental Design for a Display-Rack, of which the following is a specification, reference being had to the accompanying drawing, forming part thereof.

I claim:

The ornamental design for a display rack, as shown.

JOSEPH MARTIN PERRY.

Witnesses:

H. A. GOWN,
B. J. MIMSON.
